(57) **CLAIM**

The ornamental design for an under-cast scratching and cleansing device, as shown and described.

DESCRIPTION

FIG. 1 is a perspective view of an under-cast scratching and cleansing device of the present invention.

FIG. 2 is a front view of FIG. 1.

FIG. 3 is a rear view of FIG. 1.

FIG. 4 is a left side view of FIG. 1.

FIG. 5 is a right side view of FIG. 1.

FIG. 6 is an enlarged top view of FIG. 1.

FIG. 7 is an enlarged bottom view of FIG. 1; and,

FIG. 8 is a rear perspective view of FIG. 1.

1 Claim, 8 Drawing Sheets
